UNITED STATES PATENT OFFICE.

EDWIN JOHN SIBLEY, OF WOODHAVEN, NEW YORK.

FRICTION ADJUSTER FOR SCREENED WINDOWS.

Application filed September 1, 1923. Serial No. 360,485.

To all whom it may concern:

Be it known that I, EDWIN JOHN SIBLEY, a citizen of Canada, and resident of Woodhaven, in the county of Queens and State of New York, have invented certain new and useful Improvements in Friction Adjusters for Screened Windows, of which the following is a specification.

This invention relates to friction casement window adjusters. More particularly the invention relates to a friction type adjuster adapted to be operated through the frame of a window screen for a casement window.

In the South and in other places, local regulations often prohibit of use of casement window adjusters unless they can be operated without opening the screen, which is inside the window.

Several attempts have been made to provide casement window adjusters to be used in connection with screened casement windows, but in so far as I know, none of these have been successful and very few are in use due to unsightly complicated construction and design, absence of friction adjustment and for other reasons.

The object of this invention is to provide a friction casement window adjuster adapted to be mounted inconspicuously between the casement window and the screen and so arranged that it may be operated from within the screen and without necessitating the opening or lifting of the screen in order to open the casement window. In addition, it is an object of the invention to provide an adjuster for this purpose provided with self-adjusting friction means for holding the casement window firmly in any desired position. A still further object of the invention is to so arrange the device that it may be quickly attached to the window and window sill and only requires a small cut-out in the screen frame in order to be properly secured.

With the foregoing and further objects in view, which will be pointed out hereinafter, my invention is embodied in a friction type casement adjuster for screened windows arranged and constructed as hereinafter set forth and as illustrated in the accompanying drawings, in which

Fig. 1 is a plan view of the adjuster mounted in position between the casement window and the window screen, parts being shown in section and parts omitted;

Fig. 2 is a view in elevation of the parts

shown in Fig. 1 looking in the direction of arrow 1 and with parts broken away and parts omitted;

Fig. 3 is an enlarged sectional detail view 30 of the friction elements and adjacent parts of the adjuster;

Fig. 4 is a detail view of the locking means;

Fig. 5 is a plan view similar to Fig. 1 35 showing a different type of adjuster and with parts broken away and parts in sections;

Fig. 6 is a view in elevation of the adjuster shown in Figure 5 with parts omitted; 40

Fig. 7 is a sectional detail view of the means for releasing the locking device shown in Figs. 1 and 5;

Fig. 8 is a sectional view taken on line 45 75 8-8 of Fig. 7; and

Fig. 9 is a view looking in the direction of arrow 9 in Fig. 7.

Referring to Figs. 1 to 4, the reference numeral 10 denotes the window frame, 11 represents a casement window pivoted to the frame at 12 and 13 denotes the window screen which is conveniently shown mounted against the cleats or frame pieces 14, 14. All the foregoing parts are shown conventionally and may be of any desired construction and arrangement. The friction casement adjuster comprises a tube or barrel 15, which, in the present instant, is shown as being of rectangular cross section but which may have any other desirable form. The barrel is pivoted at 16 to a suitable bracket 17 secured to the window as by screws or other means 18. Within the barrel 15 slides an arm 19 of the same cross sectional formation as the barrel 15. The arm 19 is pivoted on a stud 20 and is provided with a handle portion 21. As seen best in Fig. 3, the stud 20 carries at its base a friction disk 22 integral with the stud. The

numeral 23 denotes a fixed base plate forming a recess 24 within which are disposed suitable friction members 25, 26, preferably in the form of disks of different metals or other suitable material. The arm 19 has a square opening 28 which fits around the square portion 29 of the stud. A casing or cover 30 through which the arm 19 passes

serves as a means for covering the connection between the arm and the stud and the friction elements. Friction is obtained between the base disk 22 of the stud and the

fixed base plate 23 by means of the nut 31 100

105

110

fixed base plate 23 by means of the nut 31

which is screwed on the stud and tightens the friction elements as may be desired and in turn press down the arm 19 on the base plate 23, the side wall 32 of the casing 30 being of course, of a suitable height so that no binding effect will occur between said side wall and the base 23, which latter is conveniently secured to the window sill 33 by means of screws 34. The base plate forms to one side an upstanding locking projection or lug 35. The adjuster handle 21 carries a spring 36 which is provided with a button 37 which projects freely upwardly through said handle, and when in the position shown in Figs. 1 and 2, the spring 36 is normally in the path of the said upstanding lug 35, the arrangement being such that when the window is closed as in Fig. 1 the spring 36 snaps in behind the lug 35 and thus prevents accidental opening of the window and operation of the adjuster. When it is desired to open the window the operator takes hold of the handle 21 and with the fore finger depresses the button 37 below the plane of the lug 35 as shown in dotted lines as shown in Fig. 3, after which the handle is swung to the left in Fig. 1, when of course, the window is opened as shown in dotted lines.

Attention is called to the fact and as clearly seen, in Fig. 2, that only a comparatively small cut-out is required in the screen frame 13 in order to mount the adjuster in proper position and this cut-out is emphasized by the heavy line 39 in Fig. 2. From the foregoing it is clear that the adjuster is inconspicuously mounted directly under the screen frame and on top of the window sill and that from the inside of the window only the handle and the casing 30 is seen while the other parts of the adjuster are hid behind the screen frame, and the window may be opened without opening the screen and will remain open in any desired position because of the friction element referred to, and which latter may be adjusted from time to time if desired by operating the nut 31 on the stud 20.

Referring now to the modifications illustrated in Figs. 5 to 9, all the corresponding and similar elements in use with those described above are similarly numbered. The modification consists in a different form of handle which when operated automatically releases the locking spring and permits operation of the adjuster.

In detail it will be seen that the handle portion 40 of the arm 19 in Fig. 5 is provided at its inner end with a bushing or sleeve 41 to which latter there is pivoted at 42 a drop handle 43. The handle has a stop 44, see Fig. 7, which takes against the underside of the sleeve 41 to maintain the handle in vertical depending position as shown in Fig. 6, and Fig. 7. When the handle is

raised by the operator its surface 45 strikes against the head 46 of a pin 47 forcing the latter to the left in Fig. 7 to depress a finger 48 which is part of the locking spring 49. The latter serves the same function as the spring 36 above described in connection with Fig. 3. The pin 47 is normally held in retracted position as shown in Fig. 7 by a coiled spring 59. As a matter of convenient construction, the handle portion 40 of the arm 19 is suitably secured within the sleeve 41 and forms a stop for the spring 49 as shown. The handle portion 40 is cut out at 50 to form a recess for the reception of the pin 47 and the bottom of said recess is open as at 51 to permit the finger 48 to project upwardly into the path of the pin 47. The spring 49 is secured in any convenient manner below the portion 40 and within the sleeve 41.

It will be seen therefore, that with respect to the friction element the adjuster illustrated in Fig. 5 operates exactly like the adjuster illustrated in Fig. 1 but that upon raising the handle 43 the locking spring is automatically depressed below the plane of the lug 35 thus permitting operation of the adjuster.

The foregoing is thought to clearly describe and illustrate my invention which not alone consists in improvements in the adjuster as such, but the invention includes and consists in the combination between the peculiar form of adjuster shown and the arrangement with the casement window and the screen therefor whereby the window may be opened without opening or manipulating the screen in any manner whatsoever and at the same time providing a friction type of adjuster for this purpose, which may be used with windows and screens of standard or usual construction, it being an important feature of this invention that my adjuster may be used with standard casement windows and screens without requiring any change in the construction of these parts. No false wood work to hide parts of the adjuster or change in the window construction or appearance is required. And in new constructions no special attention is needed to conform the windows or screens or frames or sills for the purpose of installing my adjuster, which includes as an important element the friction device for holding the window in all positions.

Another feature of the invention should be noted, namely, that operation of the adjuster through the window screen frame without manipulating the latter is possible only because all of the swinging movement of the adjuster takes place on one side of said frame (between it and the window) while the operating part of the adjuster is on the opposite (inside) side of the screen frame. In other words, it is essential for successful

operation and commercialization of the invention that the pivotal point around which the adjuster moves lies in the plane of the window screen, with the window operating parts on one side of said pivot and the handle part on the opposite side.

Whereas I have described my invention by reference to specific forms thereof, it will be understood that many changes and modifications may be made without departing from the spirit of the invention, as defined by the appended claims.

I claim:

1. The combination with a relatively fixed member and a relatively movable member, of a friction adjuster for operating the movable member through an opening in the fixed member without disturbing the latter, said adjuster comprising a pivotal support, an arm mounted to swing thereon, adjustable friction means between said pivotal support and said arm, a telescopic member carried on said arm, means for pivoting said telescopic member to the said movable member, a portion of said arm extending away from the said two members to form an operating handle and means on the latter and on the said pivotal support for automatically locking the said arm against accidental operation when said arm and movable member have been moved into a certain predetermined position.

2. The combination with a relatively fixed member and a relatively movable member, of a friction adjuster for operating the movable member through an opening in the fixed member without disturbing the latter, said adjuster comprising a pivotal support, an arm mounted to swing thereon, adjustable friction means between said pivotal support and said arm, a telescopic member carried on said arm, means for pivoting said telescopic member to the said movable member, a portion of said arm extending away from the said two members to form an operating handle, means on the latter and on the said pivotal support for automatically locking the said arm against accidental operation when said arm and movable member have been moved into a certain predetermined

position, and manually operated means on said handle for unlocking the said locking means.

3. The combination with a relatively fixed member and a relatively movable member, of a friction adjuster for operating the movable member through an opening in the fixed member without disturbing the latter, said adjuster comprising a pivotal support, an arm mounted to swing thereon, adjustable friction means between said pivotal support and said arm, a tubular member slidably supported on the latter, means for pivoting said tubular member to the said movable member in a fixed predetermined position thereon, a portion of said arm extending away from the said two members to form an operating handle, means on the latter and on the said pivotal support for automatically locking the said arm against accidental operation when said arm and movable member have been moved into a certain predetermined position, and manually operated means on said handle for automatically unlocking the said locking means.

4. The combination with a relatively fixed member and a relatively movable member, of a friction adjuster for operating the movable member through an opening in the fixed member without disturbing the latter, said adjuster comprising a pivotal support, an arm mounted to swing thereon, adjustable friction means between said pivotal support and said arm, a tubular member slidably supported on the latter, means for pivoting said tubular member to the said movable member in a fixed predetermined position thereon, a portion of said arm extending away from the said two members to form an operating handle, a lug on the said pivotal support, a spring on the said handle adapted to engage the said lug for automatically locking the said arm against accidental operation when the arm and movable member have been moved into a certain predetermined position and a manually operated member on said handle for automatically unlocking the said spring from the said lug.

EDWIN JOHN SIBLEY.
